(57) **CLAIM**

The ornamental design for a heated comb as shown and described.

DESCRIPTION

FIG. 1 is perspective view of a heated comb embodying the new design;

FIG. 2 is a front elevational view thereof;

FIG. 3 is rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the drawings illustrate a handle and an electric cord for supplying electric current to the heated comb neither of which forms a part of the claimed design.

1 Claim, 5 Drawing Sheets
